UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FOLDER FOR SEWING-MACHINES.

1,145,604.

Specification of Letters Patent.

Patented July 6, 1915.

Application filed November 26, 1906. Serial No. 345,183.

To all whom it may concern:

Be it known that I, JAMES R. MOFFATT, a citizen of the United States, residing at Chicago, in the county of Cook, State of Illinois, have invented certain new and useful Improvements in Folders for Sewing-Machines, of which the following is a description, reference being had to the accompanying drawing and to the letters and figures of reference marked thereon.

My invention relates to folders for fabrics, and while said folder may be useful for various purposes, the same is more especially adapted for folding a collaret so that the same is properly delivered to the stitching mechanism of a sewing machine whereby said folded collaret is attached to a body fabric.

An object of my invention is to provide a folder which may be adjusted so as to fold either ribbed or a plain collaret.

A further object of my invention is to provide a folder which is made in sections so that the same may be adjusted for folding collarets of different widths.

A further object of the invention is to provide an improved guiding means for guiding the strip on its way to the folder.

These and other objects will in part be obvious and will in part be more fully described hereinafter.

My invention consists in the novel parts and arrangements hereinafter shown and described.

In the accompanying drawings which illustrate one embodiment of my invention: Figure 1 is a top plan view of my improved folder and guide as shown attached to a sewing machine, the guide being shown in dotted lines in an adjusted position; Fig. 2 is an end view of the parts as shown in Fig. 1; Fig. 3 is a sectional view taken on the line $\alpha-\alpha$ shown in Fig. 1 and looking in the direction of the arrows; Fig. 4 is a view of the folder similar to Fig. 1 showing a modified form of auxiliary presser; Fig. 5 is a detail perspective of the auxiliary presser as shown in Fig. 4; Fig. 6 is a detail perspective of the auxiliary presser shown in Fig. 1; Fig. 7 is a rear view of the strip guide; Fig. 8 is a sectional view on the line 8-8 of Fig. 7 looking in the direction of the arrow; Fig. 9 is a detail perspective of the upper edge folding member; Fig. 10 is a detail perspective of the main body of the folder; and Fig. 11 is a detail perspective view of the lower folding member.

In the drawings I have shown my folder and guide as attached to a bed plate 1 of a sewing machine. The needle bar 2, the needles 3, 3, the presser bar 4, the presser foot 5, and the upper feeding member 6 are all of the usual construction and will not require further description.

My improved folder as shown in the present embodiment of my invention is made in three parts, and comprises a main body folder, an upper edge folder, and a lower edge folder and each of these parts is provided with means for adjustably supporting the same so that any one of the parts may be adjusted relative to the others.

The main body folder 7, as shown in detail in Fig. 10 consists of the guiding members 8 and 9 which are equally spaced and similarly curved so as to fold a strip intermediate its edges passing therefrom. Said members 8 and 9 are preferably joined at their outer ends and thus practically form one continuous member, at the receiving end of said folder. The outer edges however, are left free a short distance from the receiving end to the delivery end as shown in Fig. 3. This folding member gradually tapers from its receiving end toward its delivery end so that as the strip which is folded thereby leaves the delivery end, said strip is folded upon itself intermediate its edges. The guiding member 9 is made in two parts 10 and 11 which are slightly spaced so that when a ribbed or tipped collaret strip is passed through said folder a passage is provided for the rib or tip. In order to suitably support the main folding member, I have provided the same with a shank 12 which extends laterally from the body of said folder and is secured to the bed plate of the machine by means of a screw 13 passing through a slot 14 in said shank. Said shank is further retained on the bed plate by being located between the supporting member for the upper edge folder. I have also provided said shank with a stud 15 which engages

the forked end of a lever 16 pivoted at 17 to the bed plate of the machine. It will be obvious that by loosening the screw 13 the operator may adjust the main folding member laterally by manipulating the lever 16 and when said folding member is properly positioned the screw 13 is tightened, thus holding the folding member in its adjusted position. Coöperating with said main folder is an upper edge folder 18 shown in detail in Fig. 9. Said upper edge folder 18 extends the full length of the free or open edge of the main folder as shown in Fig. 4. Said upper edge folder is provided with a downwardly and inwardly turned lip 19 which extends around and beneath the free edge of the main folder as clearly shown in Fig. 3. Said upper edge folder is supported by means of two supporting members 20 and 21 which are rigidly secured to the upper folder and extend along each side shank of the main folding member and are secured to the bed plate by means of screws 22—22, and 23—23 respectively. Said supporting members 20 and 21 for the upper edge folding member are slotted as shown at 24—24, and 25—25 respectively in Fig. 9. By loosening the screws 22 and 23, it will be obvious that the upper edge folder may be adjusted transversely of the line of feed and by this adjustment the upper folding edge of the collaret may be adjusted relative to the needle or needles of the sewing machine. By this adjustment the upper edge may be so disposed relative to the two needles that both needles will engage said upper edge or that only one of said needles will engage the folded edge, while the other engages the body fabric in a line parallel to the edge and adjacent thereto, and if desired cross threads may be led from one needle to the other thus covering the edge of the collaret. The lower edge folder 26 as shown in detail in Fig. 11 has an upwardly and inwardly extending lip 27. Said lower folding member extends substantially the entire length of the free or open edge of the main folder as shown in Fig. 2 and said lip 27 extends upwardly around said free edge. In order to support said lower folding member, I have provided the same with the elongated slots 29, which receive screws 30—30. The shank of the main folder is cut away in order to expose the screws 30 and by loosening said screws 30 the lower member may be adjusted so as to properly position the lower edge of the folded collaret relative to the lines of stitching. It will be obvious that by this adjustment of the lower folder the said lower edge of the collaret may be so positioned as to receive both lines of stitching when fed to a two needle machine or so positioned as to receive only one line of stitching while the other line of stitching is located adjacent to said edge in the body

fabric and connected thereto by looper threads so as to cover the free edge of said folded strip.

The presser foot 5 has a lateral extension 31, which extends over the folded strip as it leaves the delivery end of the folder and properly holds said strip relative to the body fabric until the same has been stitched. In order to form a proper support and guide for the folded collaret, I have provided a guiding member 32, shown in detail in Fig. 6, which is attached to the shank of the main folder 7. Said guiding member 32 is provided with an enlarged attached arm having a stud 33 which engages an opening 34 in the shank 12 and a suitable screw 35 engaging an opening 36 in the shank holds said guide firmly upon the shank of the main folder. Said guide member 32 has a guiding face 37 which extends along the opening formed between the members 10 and 11 of the main folder for a short distance from its delivery end thereby closing said opening. The guiding face 37 extends beyond the delivery end of the main folder to a position substantially in a line with the needles so that the edge of a plain collaret receives support and is held in a definite position relative to the needles until said collaret is secured to the body fabric. In order to prevent the free edge of the collaret from buckling and extending up between the guiding face 37 and the presser-foot, I have provided the guide 32 with an auxiliary pressing member 38 as shown in Figs. 1 and 6. Said auxiliary pressing member has an elongated slot 39 and is secured to the guide 32 by means of a screw 40. Said auxiliary member 38 also has an upwardly directed toe 41 which prevents said pressing member from being caught by the goods passing underneath the same. When the main folder is adjusted so as to fold a wider collaret the auxiliary member 38 is adjusted so as to close up the space between the guiding face 37 and the extension 31 of the presser-foot. It will thus be seen that the main presser foot together with the auxiliary presser member covers the entire surface of the collaret and holds the same in proper position until it is stitched.

When it is desired to fold a ribbed collaret, it is necessary to remove the auxiliary presser member so as to allow the rib to pass freely through the opening between the members 10 and 11. In order to properly guide the rib, I provided a modified form of guide 42 shown in Figs. 4 and 5. Said guiding member 42 is provided with an enlarged attached arm 43¹, having a stud 44 similar to the attaching means for the guide 32. Said guide 42 has a guiding face 43 which when the guide is attached to the main shank of the folder, takes a position slightly at one side of the main folder and extends to a

point substantially in line with the needles. Said guiding face 48 also has an outwardly extending lip 47 which projects underneath the rib of the collaret and forms a support for the edge thereof.

I have provided the guiding member 42 with a presser arm 45 which is secured to the attaching arm of the guide 42 by means of a screw 46. Said arm 45 extends along the 10 face guide 43 and presses the rib of the collaret upon the lip 47 and thus serves as a means for properly guiding and holding the rib so that the collaret is properly positioned for the stitching mechanism. By mounting 15 my guide upon the shank of the main folder, it will be seen that when said folder is adjusted for different widths of collarets, said guide is also adjusted and the position of the same relative to the main folder is maintained.

My improved guide which receives and guides the strip to be folded on its way to the folder, comprises two guiding members 48 and 49 as shown in Figs. 2, 7 and 8. Said 25 members 48 and 49 are provided with outwardly extending lips 50 and 51 respectively. The lip 51 has rigidly secured thereto depending rods 52 and 53 which extend downward through suitable openings in the lip 50 at 30 the lower edge of the guiding member 48. Said rods 52 and 53 together with the guiding members 48 and 49 form a guiding passage for the strip. The guiding member 49 is provided with supporting shanks 54 and 35 55 which are rigidly secured to the member 49 and extend outwardly and downwardly and embrace the supporting posts 56 and 57 respectively which are rigidly supported by a supporting plate 57^a. The lower guiding 40 member 48 is also provided with supporting arms 58 and 59 which are rigidly secured thereto and extend outward and upward and engage the supporting posts 56 and 57 respectively. The arms for supporting 45 the guiding members 48 and 49 are adjustably secured to their supporting posts by means of set screws so that said members 48 and 49 may be adjusted relative to each other and the guiding passage formed between the said guiding members and the depending rods adjusted for different widths 50 of strips. When a ribbed collaret strip is attached to the body fabric the space between the members 48 and 49 receives said 55 rib and serves to guide the same on its way to the folder. When however, a plain strip is led through said guide it is desired to close said space and I have therefore, provided the sliding plates 60 and 61. Said 60 plate 60 is secured to the guiding member 48 by means of a screw 62. Said member 61 is also secured to the guiding member 49 by means of a slot screw 63. It will be noted 65 that the front or delivery ends of the guiding members 48 and 49 are curved inwardly

as at 64 so as to provide a smooth surface over which the fabric slides as it passes from the guide to the folder. It will also be noted that the opposite or receiving ends of the members 48 and 49 are tapered inwardly as 70 at 65 and 66 (see Fig. 7).

I have provided an auxiliary guiding means which guides the strip on its way to the main guide. Said auxiliary guide comprises depending fingers 67 and 68. Said 75 finger 67 is secured to the supporting arm 55 by means of a screw 69 and said finger extends outwardly and then downwardly substantially parallel to the guiding surfaces 48 and 49. The guiding finger 68 is secured to the supporting arm 55 by means of a screw 70 and said finger extends outwardly and then downwardly substantially parallel to the guiding surfaces 48 and 49. Said finger 68 however, is provided with a 80 U shaped projection 71 which is substantially opposite the space between the edges of the guiding members 48 and 49. Said fingers are free at their lower ends so that the strip may be easily inserted between the 85 same and when a ribbed strip is being folded said rib is received by the U shaped projection 71 and properly guided.

It will be noted that the supporting plate 57 for the strip guide is pivotally supported 95 by means of a screw 72 to the bed plate and that said guide may be angularly adjusted about said screw 72 and thus position at different distances from the folder. The object of this adjustment is so that the guide 100 may be swung out of the way to give better access to the folder when it is desired to thread the same.

The operation of my device as above described in detail is thought to be obvious. 105 The strip A to be folded is led between the fingers 67 and 68 then through the guide between the depending rods 52, 53 and the guiding members 48 and 49. The strip is then led over the smooth rounded face at 110 the front end of the guiding faces 48 and 49 to the folder. The tapered edges 65 and 66 engage the outer edges of the strip to be folded and uncurl the same. The guide as above noted is adjusted so as to properly 115 accommodate different widths of strips and when it is desired to fold a ribbed strip, the plates 60 and 61 are adjusted so as to provide a proper recess between the same for the passage of the rib. The strip after it 120 leaves the guides passes into the main folder where the same is bent upon itself intermediate its ends and the outer upper edge of said strip is received by the upper edge folding member 18 while the lower outer 125 edge of the strip is received by the lower folding member. Owing to the fact that the strips to be folded are often stretched in length by handling, which reduces the width so that the exact width of the strip when 130

it reaches the folder is not easily determined, it is often difficult to provide a finished collar of a desired width. By my improved adjustable folder the main folder 5 can be slightly adjusted either way so as to change the width of the finished collar and thus produce collars of a definite width irrespective of the width of the strip received. By the adjustment of the upper 10 and lower edge folders relative to the line of stitching the folded edges of the collar may be positioned as desired relative to the needles. It will be noted that the bed plate is cut away for the attachment of the folder 15 so that the folder when attached to my machine extends both above and below said bed plate and the center line of said folder lies substantially in the plane of the work support. I have provided the work plate with 20 an adjustable member 72 which extends to a point within the folder and serves to support the body goods passing through the machine. Said plate 75 is adjustably secured to the folder by means of a screw 73 passing 25 through a slot 74 in said plate. The object of making said plate adjustable is so that the same may be adjusted to allow for adjustments of the main folder relative to the line of stitching.

30 It will be obvious that many minor changes may be made in the details of construction above described without departing from the spirit of my invention.

Having thus particularly described my invention, what I claim as new and desire to secure by Letters Patent is:—

1. A folder including in combination a main U-shaped folder, edge folders extending along side of said main folder and co-40 operating therewith, means for supporting said edge folders whereby they may be adjusted relative to each other, and means for supporting said main folder, whereby it may be adjusted bodily laterally independently 45 of said edge-folders.

2. A folder including in combination a main folder, an upper edge folder and a lower edge folder, said edge folders being located along side of main folder and co-50 operating therewith, means for supporting said lower edge folder, means for supporting said upper edge folder, whereby it may be adjusted independently of the lower edge folder, and means for supporting said main 55 folder, whereby it may be adjusted bodily laterally independently of the edge folders.

3. A folder including in combination a main folder, an upper edge folder, a lower edge folder, said edge folders being located along side of main folder and co-60 operating therewith, means for supporting said edge folders, whereby they may be adjusted independently of each other, means for supporting the main folder, whereby it 65 may be adjusted independently of the edge

folders; and means for adjusting the main folder relative to the edge folders, and for holding the main folder in adjusted position.

4. A folder including in combination an 70 upper edge folder spaced shanks formed integral with said upper edge folder for supporting the same, a main folder, a shank formed integral therewith, and located between said spaced shanks of said upper edge 75 folder and means for holding said main folder in its adjusted positions; substantially as described.

5. A folder including in combination an 80 upper edge folder, spaced shanks formed integral therewith, and supporting said upper edge folder, a lower edge folder, a main folder co-operating with said edge folders, a shank for supporting said main folder located between the spaced shanks of the upper edge folder, means for adjusting said main folder, and means for holding the same in its adjusted positions; substantially as described. 85

6. A folder including in combination a 90 lower edge folder, a shank for supporting said lower edge folder, means for holding said shank in its adjusted positions, a main folder, a shank for supporting said main folder mounted upon the shank of said lower 95 edge folder, means for adjusting said main folder laterally bodily independently of said lower edge folder and means for holding the same in its adjusted positions; substantially as described. 100

7. A folder including in combination a lower edge folder, a shank for supporting said lower edge folder, a main folder, a shank for supporting said main folder formed integral therewith and mounted 105 upon the shank of the lower edge folder, an upper edge folder, spaced shanks for supporting said upper edge folder mounted upon the shank of said lower edge folder and means for adjusting said main folder 110 and means for holding said main folder in its adjusted positions; substantially as described. 110

8. The combination with a work support, of a folder secured thereto, means for adjusting said folder upon said work support and a supporting plate adjustably secured to said work support and extending within said folder; substantially as described. 115

9. The combination with a slotted work 120 support, a folder located within the slot in said work support, means for adjustably supporting said folder, and a supporting plate secured to said work support and extending over the slot in said work support 125 to a point within said folder; substantially as described.

10. The combination with a work support, 130 stitch forming mechanism including a needle, a folder located in front of said needle,

- comprising a main folder, an upper edge folder and a lower edge folder, and means for adjusting the members of said folders independently of each other and relative to said needle; substantially as described. 5
11. The combination with a work support, stitch forming mechanism, a presser foot, a folder located in front of the presser foot, and including a main folder, an upper edge folder and a lower edge folder, and means for adjusting each of the members of said folder independently of the others, and an auxiliary pressing member for the folded strip passing through the folder, said auxiliary pressing member being located at one side of the presser foot. 10
12. The combination with a folder comprising a main folder and edge folders, said main folder having spaced members to receive a tip or rib formed upon the folded strip, a guiding member for closing the space between said members at the delivery end, when said folder is used for folding a plain strip; substantially as described. 15
13. The combination with a work support, stitch-forming mechanism, a presser-foot, of a folder comprising a main folding member having members which are spaced to form a guide way for the tip or rib of the strip to be folded, of a guiding member for closing the space between said members at the delivery end of said folder, said guiding member extending beyond said folder to a point adjacent the stitching point so that the folded strip is guided to said stitch-forming mechanism; substantially as described. 20
14. The combination with a folder of means for guiding a strip to said folder comprising guiding members having the delivery end thereof curved located at an angle to the longitudinal axis of the folder and means for adjusting said guiding members so as to accommodate strips of different widths; substantially as described. 25
15. The combination with a folder of means for guiding a strip to said folder comprising guiding members, means for adjusting said guiding members relative to each other, and means for closing the space between said guiding members; substantially as described. 30
16. The combination with a folder of means for guiding a strip thereto, said guiding means being located at an angle to the longitudinal axis of said folder and having edges tapering toward the center of said guiding means and a guiding device in advance of said guiding means for holding the strip against said tapered edges, whereby the edges of the guided strip may be uncircled; substantially as described. 35
17. The combination with a folder, of means for guiding a strip thereto, comprising guiding members arranged substantially at right angles to the longitudinal axis of
- said folders and having the delivery end thereof located in front of said folder, said end being curved to form a smooth surface over which the strip is led to the folder, and means for supporting the said guiding members independently of the folder; substantially as described. 40
18. The combination with a folder comprising a main folding member having members which are spaced to receive a rib or tip on the strip to be folded, of guiding means for said strip comprising guiding members which are spaced to provide a guiding recess for the rib or tip of said strip; substantially as described. 45
19. The combination with a folder of means for guiding a strip to said folder comprising guiding members, means whereby said guiding members may be adjusted relative to each other, means for closing the space between said guiding members and guiding fingers for guiding the strip to said guiding means; substantially as described. 50
20. A folder including in combination a main folder, an upper edge folder and a lower edge folder and a lever for adjusting said main folder relative to said edge folders and means for holding said main folder in its adjusted positions; substantially as described. 55
21. A folder including in combination a main folder, a lower edge folder, a shank for supporting said lower edge folder, an upper edge folder, and a lever mounted upon the shank of said lower edge folder and engaging a stud carried by said main folder, whereby said main folder may be adjusted and means for holding said main folder in its adjusted positions; substantially as described. 60
22. The combination with a folder of means for guiding a strip to said folder comprising a pivoted supporting plate, posts carried by said plate, adjustable members carried by said posts for guiding the strip, means for closing the space between said adjustable members, and auxiliary guiding fingers for guiding the strip to said guiding means; substantially as described. 65
23. The combination with a work support, stitch-forming mechanism and a presser-foot, of a folder, means for adjustably securing said folder to said work support, means for guiding a strip to said folder and an adjustable plate carried by said work support and extending within said folder; substantially as described. 70
24. In a folding device, a main folder having a receiving opening of constant dimensions, a guiding channel leading therefrom, supplemental folders having scrolls substantially in line with said receiving opening in the main folder, and co-operating with the guiding channel to guide and fold the edges of a strip. 75

25. In a folding device, a main folder, supplemental folders arranged at the top and bottom of the main folder, said main folder being provided with a longitudinal 5 groove and a shank mounted upon both sides of said longitudinal groove and having a passage between the arms of said shank; substantially as described.

26. A sewing machine including a work 10 support having a slot cut therein for a folding device, a folding device comprising three independent parts, the central portion being upon each side of the work support, the top part above the work support and the 15 lower part below said work support; substantially as described.

27. A sewing machine including a work support having a slot cut therein for a folding device, a folding device comprising three 20 parts, the central portion being upon each side of the work support, the top part above the work support and the lower part below said work support, and an independent guide in advance of the work support and 25 extending above and below said work support; substantially as described.

28. In a folding device, a main folder having a receiving opening of constant dimensions, a guiding channel leading therefrom, edge folders located substantially in 30 line with said receiving opening in the main folder, and coöperating with the guiding channel to guide and fold the edges of a strip, means for supporting said edge folder 35 independently of the main folder, and means for adjusting the main folder independently of the edge folders.

29. In a folding device, a main folder having a receiving opening, a guiding channel leading therefrom, edge folders coöperating with the guiding channel to form an 40 edge-folding portion to guide and fold the edge of a strip, means for adjusting the

capacity of the folder, and a lever for effecting said adjustment.

30. A folding device including a portion to give a fold to the strip, a second portion to receive the strip from the first portion and coöperating therewith to fold the edges of the same, and means for imparting relative movement to said portions transversely of the line of the feed of the strip.

31. A folding device including a portion to give a fold to the strip, a second portion to receive the strip from the first portion 55 and coöperating therewith to fold the edges of the same, means for imparting relative movement to said portions transversely of the line of the feed of the strip, and means for adjusting the second folding portion to 60 accommodate a strip having varying widths.

32. A folding device including a portion to give a fold to the strip, a second portion to receive the strip from the first portion and coöperating therewith to fold the edges 65 of the same, and having means for turning the edges of the strip, and means for imparting a relative movement to said portions transversely of the line of the feed of the strip.

33. A folding device including a portion to give a fold to the strip, a second portion separate from the first portion to receive the strip from the first portion and coöperating therewith to fold the edges of the same, the 75 walls of said second folding portion at the delivery end being spaced a less distance apart than the walls of the initial folding portion.

In testimony whereof I affix my signature, 80
in presence of two witnesses.

JAMES R. MOFFATT.
